UNITED STATES PATENT OFFICE.

SAMUEL M. LUCAS, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed May 3, 1927. Serial No. 188,473.

My invention relates to railway traffic controlling apparatus, and particularly to apparatus which is responsive to periodically varying current in the trackway. More particularly my invention relates to train carried apparatus for multiplying the frequency of the impulses received from the trackway.

I will describe one form of apparatus embodying my invention, and will then point out the novel features thereof in claims.

In the accompanying drawings Fig. 1 is a diagrammatic view of one form of railway traffic controlling apparatus embodying my invention. Figs. 2, 3 and 4 are views showing a few modifications of a portion of the apparatus illustrated in Fig. 1, and also embodying my invention.

Similar reference characters refer to similar parts in each of the several views.

Referring first to Fig. 1, the reference characters 1 and 1^a designate the track rails of a stretch of railway track, over which traffic normally moves in the direction indicated by the arrow. These rails are divided into sections by means of insulated joints 2, only one complete section, A—B, being shown. Train controlling current is at times supplied to the rails of this section from a suitable source of energy, such as an alternator G. The current supplied to the trackway by this alternator may be of a frequency of the order of the usual commercial alternating current such, for example, as 60 or 100 cycles per second.

The supply of current to the track rails is controlled by a coding device designated in general by the reference character Z and comprising a plurality of rotatable insulated cams each designated by the reference character C with an appropriate distinguishing exponent. These cams are driven at a constant speed by means of a motor P supplied with current from the alternator G. The cam C¹ is provided with spaced swells 8 about its periphery, and when the cam is rotated these swells successively engage a contact 3 to periodically close the contact. Similarly cams C² and C³ are provided with different numbers of swells 8 for controlling contacts 4 and 5, respectively. One terminal of the alternator G is constantly connected with rail 1 of the section A—B and the other terminal of the alternator is connected with the rail 1^a through one

of the contacts 3, 4 or 5 depending upon traffic conditions.

It will now be apparent that the alternating current supplied to the rails of the trackway will be periodically varied at the frequency of operation of the contacts of the device Z which is connected between the alternator and the track rail 1^a. By way of example, I have shown cam C¹ as provided with four swells, cam C² with six swells and cam C³ with nine swells and will assume that these cams are rotating at 20 revolutions per minute. The selection between the contacts of the device Z in accordance with traffic conditions may be accomplished in any suitable manner, and as here shown this selection is made by means of two relays H and L. Since the circuits of these relays form no part of my present invention, it will be sufficient to state that when both of the sections in advance of point B are unoccupied, relays H and L are both energized and the contact 5 is connected in the trackway circuit. When the second section in advance of point B is occupied by a train, relay H is energized, whereas relay L is de-energized and contact 4 is then connected in the trackway circuit. When the section immediately in advance of point B is occupied by a train, both of the relays H and L are de-energized and the contact 3 is connected in the trackway circuit. It will be clear that when contact 5 is connected in the trackway circuit, the alternating current supplied to the circuit will be periodically varied at a frequency of 180 cycles per minute corresponding to what I shall hereinafter term the "proceed code". When contact 4 is connected in the trackway circuit, the alternating current will be varied at a frequency of 120 cycles per minute which current I shall term the "caution code". Similarly, when contact 3 is connected in the trackway circuit the alternating current will be varied at a frequency of 80 cycles per minute which I shall term the "slow code".

The reference character V designates a train having a forward axle 25 and carrying governing means which is responsive to the varying current in the trackway. Mounted transversely with respect to the track rails 1 and 1^a and in front of the forward axle 25, are two magnetizable cores 9 and 9^a, carrying windings 10 and 10^a, respectively. These

windings are so connected that the electro-motive forces induced therein by currents flowing in opposite directions in the two track rails at a given instant, are additive. Windings 10 and 10^a are connected with the primary of a transformer Q through an amplifier 11 which may be of the electron tube type. The secondary of transformer Q is connected with the winding of a relay M. This relay is of the polarized type and has an armature 12 which co-operates with normal, middle and reverse contacts 12^a, 12^b and 12^c, respectively. When train controlling current is being supplied to the trackway, pulsating energy is delivered to the primary of transformer Q at the frequency of the periodic variations in the trackway current. For each impulse of energy supplied to transformer Q, during an increase in such current, an impulse of one relative polarity is supplied to the relay M, and during the decrease in such current an impulse of the opposite relative polarity is supplied to the relay. The relay M is responsive to the relative polarity of the current supplied to it so that when the trackway current is being periodically varied, the relay M is operated to close its normal and reverse contacts 12—12^a and 12—12^c alternately at a frequency which corresponds to the frequency of the variations of the trackway current, and twice during each cycle of operation this relay closes the intermediate contact 12—12^b.

In apparatus of the type in which the selection between codes is performed by means of electrically tuned circuits, it may be desirable to multiply the code frequency of the current supplied to these circuits so that the tuning may be more easily accomplished. In order to effect this multiplication, I provide means for producing alternating current of a frequency greater than, but proportional to, the frequency of the impulses supplied to the relay M. This is accomplished by means of a chain of cascade-connected polarized relays, each designated by the reference character R with a suitable distinguishing exponent. As here shown, this chain comprises three relays R¹, R² and R³ each having an armature 13 which co-operates with three contacts 13^a, 13^b and 13^c similar to the contacts of relay M. When relay M is energized in one direction so as to close its contact 12—12^a, current flows from terminal 14^a of battery S through contact 12—12^a, wire W¹, winding of relay R¹ and wire 15 to terminal 14 of battery S. I will assume that with this circuit closed the current is of such polarity as to close contact 13—13^a of relay R¹. When relay M is energized in such direction as to close its contact 12—12^c current flows from terminal 14^a of battery S, through wire 26, contact 12—12^c, wire W¹, winding of relay R¹ and wire 15 to terminal 14 of battery S. It will be clear that the current flow through the winding of re-

lay R¹ is again in such direction as to close the contact 13—13^a. During its travel from one extreme position to the other, armature 12 closes the contact 12—12^b to complete a circuit from terminal 14 of battery S through wire 15, winding of relay R¹, wire W¹, contact 12—12^b of relay M and wire 27 to terminal 14^b of battery S. When this circuit is closed the polarity of the current supplied to the winding of relay R¹ is such as to close contact 13—13^c. It will be evident, therefore, that while armature 12 is traveling from one extreme position to the other the polarity of the current supplied to the winding of relay R¹ is changed twice and consequently armature 13 of relay R¹ travels from one extreme position to the other and back to its initial position during this time. In other words relay R¹ operates at twice the frequency of operation of relay M. Relay R² is controlled by the relay R¹ in the same manner that relay R¹ is controlled by relay M, so that relay R² operates at twice the frequency of operation of relay R¹. In a similar manner relay R³ is controlled by relay R² so that relay R³ operates at twice the frequency of operation of relay R², or at eight times the code frequency at which relay M operates. The circuits for relays R² and R³ will be obvious from those already described.

Associated with the last relay of the chain, here shown as relay R³, is a transformer T, the primary 16 of which is controlled by the armature 13 of this relay. When relay R³ is energized in such direction that its contact 13—13^a is closed, current flows from terminal 14^a of battery S through wire 26, contact 13—13^a of relay R³, primary 16 of transformer T, and wire 15 to terminal 14 of battery S and a similar circuit is closed over contact 13—13^c of this relay when contact 13—13^c is closed. During the travel of armature 13 from one extreme position to the other, contact 13—13^b is closed momentarily to complete a circuit from terminal 14 of battery S through wire 15, primary 16 of transformer T, contact 13—13^b of relay R³ and wire 27 to terminal 14^b of battery S.

It will now be clear that the polarity of the current supplied to the primary 16 of transformer T will be changed twice during each movement of armature 13 of relay R³ from one extreme position to the other, or four times for each cycle of operation of this relay, so that the alternating current induced in secondary 17 of transformer T will be of twice the frequency of operation of relay R³. It will be plain from the foregoing explanation, that when periodically varying current is supplied to the track rails, the relay M and the chain of relays R will operate to produce alternating current in the secondary 17 of transformer T, and that the frequency of this current will be of sixteen times the frequency of the impulses supplied to relay M.

Connected to the secondary 17 of the transformer T, for the purpose of selecting between the codes supplied to the trackway, are a plurality of parallel connected tuned circuits F¹, F² and F³, each tuned to resonance at a frequency which is a multiple of the frequency of one of the codes supplied to the track rails by the coding device Z. The circuit F³ comprises a condenser 18 and a reactor 19, and as here shown this circuit is tuned to resonance at a frequency which is sixteen times the frequency of the proceed code. Similarly, circuits F² and F¹ are tuned to resonance at frequencies which are sixteen times the frequencies of the caution and slow codes, respectively. Associated with the circuit F³ is a relay K³, which is supplied with current through a rectifier D³, the rectifier being connected across a portion of the reactor 19. In a similar manner, circuit F² supplies current to a relay K² through a rectifier D², and circuit F¹ supplies current to a relay K¹ through a rectifier D¹.

In describing the operation of the apparatus, I will first assume that the two track sections in advance of point B are unoccupied so that relays H and L are both energized. Under these conditions the contact 5 connects the alternator G with the trackway circuit thereby supplying the trackway circuit with the proceed code consisting of 180 impulses per minute. The relay M will now operate at the frequency of the proceed code, and current of a frequency which is of sixteen times the frequency of the impulses of the proceed code will be supplied to the secondary 17 of transformer T. The circuit F³ being tuned to resonance at this frequency, the current supplied to relay K³ will energize this relay, causing it to close its front contact 20-20^a, thus lighting a lamp 21 which is supplied with current from a battery J. This lamp will remain lighted as long as the proceed code is supplied to the track rails.

When the second section in advance of point B is occupied by a train so that relay H is energized and relay L is de-energized, contact 4 is connected with the trackway circuit so that the caution code is supplied to this circuit. The relay M will operate at the frequency of the caution code and the chain of relays will operate to multiply this frequency to produce alternating current of the frequency to which the circuit F² is tuned. Under these conditions, relay K² will be energized but since circuits F³ and F¹ are not tuned at this frequency relays K³ and K¹ will both de-energized, and the lamp 22 will be lighted over the back contact 20-20^b of relay K³ and front contact 20-20^a of relay K² to give a caution indication.

I will now assume that the track section immediately in advance of point B is occupied by a train so that the relay H is de-energized and contact 3 is connected in the track-

way circuit. The slow code consisting of 80 impulses of current per minute will now be supplied to the relay M and alternating current of the frequency to which the circuit F¹ is tuned will be supplied by the transformer T. Under these conditions, relay K¹ will be energized but relays K³ and K² will be de-energized, so that lamp 23 will be lighted over back contact 20-20^b of relay K³, back contact 20-20^b of relay K², and front contact 20-20^a of relay K¹, and will remain lighted as long as the slow code is supplied to the track rails.

If for any reason the supply of current to the secondary 17 of transformer T ceases, the relays K¹, K² and K³ will all be de-energized and lamp 24 will be lighted over the back contacts of all the relays K¹, K² and K³ to give a stop indication. It will also be understood that if the coding device Z supplies alternating current of constant amplitude or fails to supply current to the track rails, the relay M will cease to operate and the chain of relays will cease to operate so that the polarity of the current supplied to the primary of transformer T will be unchanged and no alternating current will be induced in the secondary 17 of transformer T. Under these conditions, the relays K¹, K² and K³ will all be de-energized and lamp 24 will be lighted to give a stop indication as before.

Under some conditions it may be desirable to operate the apparatus from a source of energy, such as a head-light generator not provided with a mid-tap. This may be accomplished with the arrangement shown in Fig. 2 where the relay M is controlled in response to the periodic variations in the track-way current as in Fig. 1. Associated with each of the chain of relays R¹, R² and R³ is a bridge device each designated by the reference character E with a suitable distinguishing exponent and each comprising four resistors 28, 29, 30 and 31. The electro-motive force of the generator X is constantly supplied through wires 27 and 28 across each of the bridge devices E¹, E², etc., wire 27 being connected with the common terminal of resistors 28 and 29 of each of these devices and wire 26 being connected with the common terminal of resistors 30 and 31 of each of these devices. The winding of relay R¹ is connected from the common terminal of resistors 28 and 31 to the common terminal of resistors 29 and 30 of device E¹, and each of the remaining relays R is similarly connected with the associated bridging device E. The resistor 31 of each bridging device E is chosen to have a larger resistance than that necessary to produce the balanced condition of the bridge for which no current will flow in the associated relay R. Contacts 12-12^a and 12-12^b of relay M are connected in parallel across the resistor 31 of bridging device E¹. It follows that whenever either of these contacts is closed, a path

of low resistance is completed around resistor 31, thereby shunting this resistor. Assuming that the upper terminal of generator X is positive, then when the shunt path 5 around resistor 31 is open, current flows in one direction through relay R¹ because the potential of the common terminal of resistances 28 and 31 is higher than the potential of the common terminal of resistances 29 and 30, 10 and when resistor 31 is short-circuited, current flows in the other direction through relay R¹ because the potential of the common terminal of resistances 29 and 30 is then higher than the potential of the common 15 terminal of resistances 28 and 31. When relay M is operating intermittently, therefore, each time contact 12-12^a is closed, relay R¹ is energized in one direction, which I will assume to be the direction in which contact 20 13-13^a of this relay is closed. When relay M is next reversed, an interval of time elapses during which both contacts of relay M are open and during which the path of low resistance around resistor 31 is open. 25 During this interval of time relay R¹ closes its contact 13-13^a. When contact 12-12^a of relay M becomes closed relay R¹ is again reversed, to close its contact 13-13^a. In similar manner during operation of relay M 30 from the position in which contact 12-12^a is closed to the position in which contact 12-12^a is closed, relay R¹ moves through a complete cycle of operation, closing contact 13-13^a and returning to the position in which 35 contact 13-13^a is closed. It follows therefore that for each complete cycle of operation of relay M, relay R¹ makes two complete cycles. In similar manner, relay R² makes two complete cycles for each single cycle of relay R¹, and relay R³ makes two complete 40 cycles for each single cycle of operation of relay R². Relay R³ is provided with two contact armatures 13 and 32, which operate as pole-changers to periodically reverse the polarity of the current supplied from wires 45 26 and 27 to primary 16 of transformer T, as will be apparent from the drawing. The current thereby induced in secondary 17 of transformer T may be utilized to operate the 50 relays K¹, K² and K³ in the manner already explained in connection with Fig. 1.

In the modification shown in Fig. 3, each of the relays R comprises two windings 33 and 34 controlling an armature 35 which actuates the contact 13. Winding 34 of the relay R is constantly connected across wires 26 and 27 and tends to move the armature 35 to a position in which contact 13-13^a is closed. Winding 33 of relay R¹ is connected across wires 26 and 27 when either contact 12-12^a or 12-12^b of relay M is closed. When winding 33 is energized, the effect of this winding upon armature 35 predominates over the effect of winding 34 upon this armature, 60 thereby reversing the armature and closing

contact 13-13^a. It follows that when either the normal or the reverse contact of relay M is closed, contact 13-13^a of relay R¹ is closed. When relay M is being operated in accordance with the periodic variations in the trackway current, however, relay R¹ is reversed to close its contact 13-13^b during the intervals that the contacts of relays M are both open. It follows that relay R¹ operates at twice the frequency of operation of relay M. Each of the remaining relays R in the chain is controlled by the preceding relay in the chain in the manner just described for the control of relay R¹ by relay M. The contacts 13 and 32 of relay R³ periodically reverse the current supplied to the primary 16 of transformer T in the same manner as in Fig. 2.

Referring now to Fig. 4, the chain of polarized relays R¹, R² and R³ is replaced by a chain of neutral relays r¹, r² and r³ each having an armature 34 positively biased to a position in which contact 34-34^a is closed by a spring 36. When one of the relays r is energized, however, the associated armature 34 is moved against the bias of the spring 36 to a position in which contact 34-34^a is closed. Relay r¹ is arranged to be energized when either of the contacts 12-12^a or 12-12^b of relay M is closed, the circuit for this relay passing from wire 27, through the winding of the relay and thence through the contacts of relay M in parallel to wire 26. Each time one of the contacts of relay M is closed, therefore, relay r¹ becomes energized, but during the interval between successive energizations of relay r¹, its back contact 34-34^b is closed. Relay r² is controlled by the contacts of relay r¹ in the same manner that relay r¹ is controlled by relay M. It will be plain, therefore, that the arrangement of apparatus shown in Fig. 4 supplies to the primary of transformer T a periodic current the frequency of which is proportional to, but higher than the frequency of operation of relay M.

Although I have herein shown and described only a few forms of railway traffic controlling apparatus embodying my invention, it is understood that various changes and modifications may be made therein without departing from the spirit and scope of my invention.

Having thus described my invention, what I claim is:

1. Railway traffic controlling apparatus comprising a stretch of railway track, means for supplying periodically varying currents to said stretch, a main train carried relay responsive to such variations but not to the current itself, a second relay controlled by said main relay and operating at a frequency higher than, but proportional to the frequency of operation of the main relay, and gov-

erning means selectively responsive to the frequency of operation of said second relay.

2. Railway traffic controlling apparatus comprising a stretch of railway track, means for supplying periodically varying current to said stretch, a source of direct current, a main train carried relay responsive to the current variations and having normal and reverse contacts and an intermediate contact, a second relay responsive to the polarity of the current supplied thereto, means controlled by the main relay for supplying said second relay with current of one polarity when either said normal or reverse contact is closed but with current of the other polarity when said intermediate contact is closed, and governing means selectively responsive to the frequency of operation of said second relay.

3. Railway traffic controlling apparatus comprising a stretch of railway track, means for supplying periodically varying current to said stretch, a main train carried relay responsive to the variations in such current and having normal, intermediate and reverse contacts, a second relay, means for supplying current of one polarity to said second relay when either the normal or reverse contact of the main relay is closed and current of the other polarity when the intermediate contact is closed, and governing means selectively responsive to the frequency of operation of said second relay.

4. Railway traffic controlling apparatus comprising a stretch of railway track, means for supplying periodically varying current to said stretch, a source of direct current, a main train carried relay responsive to the current variations and having normal and reverse contacts connected to one terminal of said source and an intermediate contact connected to the other terminal of the source, a second relay connected between the mid-point of said source and the armature of said main relay and operating at twice the frequency of operation of the main relay, and governing means selectively responsive to the frequency of operation of said second relay.

5. Railway traffic controlling apparatus comprising a stretch of railway track supplied with alternating current periodically varied at different frequencies, a train carried relay responsive to the current variations, means including a chain of cascade-connected relays for producing alternating currents of frequencies which are multiples of the frequencies of such current variations, and governing means selectively responsive to said currents of higher frequency.

6. Railway traffic controlling apparatus comprising a stretch of railway track, a source of periodically varying current for said stretch, a main train carried relay responsive to the variation in said current, a source of direct current, a second relay connected with the direct current source, means

controlled by said main relay for reversing the polarity of the current supplied to the second relay from said source of direct current, and governing means selectively responsive to the frequency of operation of said second relay.

7. Railway traffic controlling apparatus comprising a stretch of railway track supplied with periodically varying alternating current, a main train carried relay responsive to the current variations, a source of direct current, a second relay and a transformer connected to said source, means controlled by the main relay for periodically reversing the polarity of the current supplied to the second relay, means controlled by the second relay for reversing the current in the primary of the transformer at a frequency proportional to, but greater than, the frequency of the reversals in the current supplied to the second relay, and governing means connected to the secondary of the transformer and selectively responsive to the frequency of the current reversals in said primary.

8. Railway traffic controlling apparatus comprising a stretch of railway track, a source of periodically varying current for said stretch, a main train carried relay responsive to the current variations, means controlled by said main relay and including a chain of cascade-connected relays for producing alternating current of a frequency greater than, but proportional to, the frequency of such current variations, and governing means selectively responsive to the frequency of the alternating current.

9. Railway traffic controlling apparatus comprising a stretch of railway track, means for supplying periodically varying alternating current to said stretch, a main train carried relay receiving energy from the trackway, said relay having a normal and a reverse contact and operating at a frequency depending upon the frequency of such current variations, an intermediate contact on said relay arranged to be closed twice during each cycle of operation of the relay, a polarized relay controlled by said main relay and energized in one direction when either the normal or reverse contact of the main relay is closed but energized in the other direction when the intermediate contact is closed, and governing means responsive to the frequency of operation of the polarized relay.

10. Railway traffic controlling apparatus comprising a stretch of railway track, means for supplying periodically varying current to said stretch, a main train carried relay responsive to such current variations, a source of direct current, a chain of cascade-connected relays controlled by said main relay, a transformer having a primary circuit connected between the mid-point of said source and the armature of the last relay of the chain, means controlled by said last relay for

reversing the polarity of the current supplied to said primary circuit four times for each cycle of said last relay, and governing means connected to the secondary of said transformer and selectively responsive to the frequency of the current reversals in said primary.

11. In combination, a main relay, means for operating the main relay periodically at different frequencies, a second relay, means controlled by the main relay for operating the second relay at twice the frequency of operation of the main relay, and means selectively responsive to the frequency of operation of the second relay.
- 15 12. In combination, a main relay, means for operating the main relay periodically at dif-

ferent frequencies, a second relay, means controlled by the main relay for operating the second relay at a frequency which is a multiple of the frequency of operation of the main relay, a transformer having its primary supplied with direct current, means controlled by the second relay for reversing the polarity of the current supplied to said primary at a frequency which depends upon the frequency of operation of said relay, and means selectively responsive to the frequency of the electromotive force induced in the secondary of said transformer. 25

In testimony whereof I affix my signature.

SAMUEL M. LUCAS.
